(57) **CLAIM**

The ornamental design for a skin care device as shown and described.

DESCRIPTION

FIG. 1 is a perspective view of a skin care device showing my new design;

FIG. 2 shows a front view thereof;

FIG. 3 shows a rear view thereof;

FIG. 4 shows a left view thereof;

FIG. 5 shows a right view thereof;

FIG. 6 shows a top view thereof; and,

FIG. 7 shows a bottom view thereof.

The broken lines shown in the figures are for the purpose of illustrating portions of the skin care device, which form no part of the claimed design.
